UNITED STATES PATENT OFFICE.

HENRY O. JACKSON, OF DENVER, COLORADO, ASSIGNOR TO THE JACKSON COMPRESSOR COMPANY, OF DENVER, COLORADO, A CORPORATION OF COLORADO.

ROTARY AIR-COMPRESSOR.

1,197,578.

Specification of Letters Patent. Patented Sept. 5, 1916.

Application filed January 12, 1914. Serial No. 811,506.

To all whom it may concern:

Be it known that I, HENRY O. JACKSON, citizen of the United States, residing in the city and county of Denver and State of Colorado, have invented certain new and useful Improvements in Rotary Air-Compressors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in rotary air-compressors, my object being to provide a construction having great efficiency or capacity as compared with its size or bulk, making it practicable to confine 20 within comparatively small space a machine of large air compressing capacity.

My further object is to provide a construction of increased efficiency as compared with the power expended in its operation.

25 My further object is to provide a construction of this class which shall be exceedingly economical in cost as compared with its efficiency.

It is exceedingly important in machines 30 of this class, to reduce the bulk, and also the weight, to the lowest possible limit, since an important use for a machine of this class is the operation of rock-drilling machines, which are often employed in sections 35 where transportation is difficult, as in rugged or mountainous regions. Furthermore, it is often exceedingly important to have an air-compressor that shall occupy little space as compared with its capacity, 40 owing to the limited accessible space for these machines.

Attention is called to the fact that my improved construction may be employed for pumping liquids as well as in the compression of air or other gases. Hence, whenever the term "air compressor" is employed, it must be interpreted as sufficiently comprehensive to include a construction for pumping liquids as well as adapted for use in 45 compressing air or other gaseous fluids. From this, it will be understood that the same construction may be either an air compressor or a pump for fluids of all kinds, without changing its mechanical organiza-

tion, or departing from the spirit of the 55 invention.

Speaking more specifically, my improved construction consists of a rotary element eccentrically mounted within a chamber, upon a driven shaft having its axis co-incident with the axis of the chamber. Fitted around this eccentrically mounted element, which is cylindrical in shape, is a series of rings which are movable upon the eccentric and which are connected with the inner 60 extremities of oscillatory blades, whose outer extremities engage sockets formed in the casing or stationary wall of the chamber. The inner extremity of each oscillatory blade is preferably connected with a 65 pair of the rings which surround the eccentric, each blade having its inner extremity anchored in rings which are movable independently of the rings in which the inner extremities of the other blades are respec- 70 tively anchored. This makes it practicable for the blades to respectively assume their necessary positions during the rotation of the eccentric, and is necessary since no two of the air compressing blades maintain the 75 same relation at their inner extremities at all times.

The air compressing chamber is in communication with concentrically arranged chambers formed in the casing, through the 80 instrumentality of inlet and exhaust check valves. One set of valves opens inwardly in response to the vacuum condition produced in the respective compartments as the blades move to enlarge said compartments, 85 while the other set of valves opens outwardly to permit the escape of the compressed air as the said compartments are contracted, due to the changed relation of the blades which constitute the movable 90 walls of the compartments. Between the eccentric and the rings in which the inner extremities of the blades are anchored, is preferably located a bushing sleeve which reduces the friction between the eccentric 95 and the blade anchoring rings.

Having briefly outlined my improved construction I will proceed to describe the same in detail, reference being made to the accompanying drawing in which is illustrated 100 105 an embodiment thereof.

In this drawing: Figure 1 is an end elevation of my improved air-compressor,

Fig. 2 is a side view of the same, or a view looking in the direction of arrow *a*, Fig. 1. Fig. 3 is a detail view of one of the check valves shown on a larger scale than Figs. 5 1 and 2. Fig. 4 is a section taken on the line 4-4, Fig. 3. Fig. 5 is a section taken on the line 5-5, Fig. 2, the parts being shown on a larger scale. Fig. 6 is a section taken on the line 6-6, Fig. 1, shown on a 10 larger scale. Figs. 7 and 8 are fragmentary views partly in section illustrating the manner of connecting the inner extremities of the blades with the rings surrounding the eccentric element in order to form fluid tight 15 joints between the compartments; Fig. 9 is a fragmentary sectional view illustrating the outer extremity of the stem of the inlet valves, together with its attachments; Fig. 10 is a detailed view showing a two-part 20 ring forming a part of the construction as shown in Fig. 9.

The same reference characters indicate the same parts in all the views.

Let the numeral 5 designate the body or 25 cylindrical wall of my improved air-compressor, the same being equipped with heads 6 which are secured to the body member by bolts 7. The outer portion of the body member is reinforced as shown at 8, and in it are 30 formed concentrically arranged inlet and exhaust chambers 9 and 10, which are intersected by check valve casings 12 and 13, 12 being the casings for the inlet valves and 13 the casings of the outlet or exhaust valves.

35 The inlet valves consist of valve pieces 14 engaging seats 15 formed on the inner extremities of the casings 12, which are threaded into the inner portion of the body member as shown at 16. These valve pieces are provided with stems 17 which pass through interior guides 18 formed integral with the casings 12. The stems are surrounded by spiral springs 19, whose inner extremities engage spider arms 20, integral with the 40 guides 18, and whose outer extremities bear against collars 21, having exterior sockets 22 in which are fitted rings 23 engaging circumferential grooves 24 formed in the stem. These rings are each composed of two parts 45 25, and they constitute stops which engage the collars 21 and prevent the valve pieces 14 from moving inwardly into the air compressing chamber 26. The outer extremities of the springs 19 engage the collars 21 and 50 retain the latter in their proper relative position and in co-operative engagement with the stop rings 23. The springs 19 should be of such tension as to normally maintain the valve pieces in contact with their seats. The 55 casings 12 of the inlet valves are provided with openings 27, whereby the chambers of these casings are in communication with the annular chamber 9 of the body member of the structure.

60 The outlet or exhaust valves are similar

in construction, except that the valve pieces 28 open outwardly, their stems 29 entering recesses 30 formed in guide lugs 31 integral with the outer extremities 32 of the casings 13. The stems of these valves are surrounded by spiral springs 33 whose outer extremities bear against the casing ends 32, while their inner extremities engage the valve pieces 28. The seats 34 of the exhaust valves are threaded into the inner extremities of the casings, which are interiorly threaded therefor, the said casings being exteriorly threaded, as shown at 35, to engage threaded openings formed in the inner portion of the body member.

70 Journaled within the heads 6 of the body structure, which are provided with hubs 36 and webs 37, is a driven shaft 38, to which is secured by means of a key 39 a cylindrical element 40, which is connected with the 75 shaft beyond the center of the said element, whereby as the shaft is rotated the element 40 by virtue of its eccentric mounting within the chamber 26 will impart the necessary throw to the blades 41, whose inner extremities are cylindrical, as shown at 42, and engage sockets 43 formed in rings 44 which surround the member 40, which may be termed the eccentric.

80 As illustrated in the drawing, a bushing 45 is interposed between the outer surface of the eccentric and the rings 44 for the purpose of reducing the friction between the rings and the eccentric. This sleeve may, however, be dispensed with, and in that event the rings would be closely fitted to the exterior surface of the eccentric.

85 As illustrated in the drawing, (see Fig. 6) the inner extremity of each blade 41, except one, is provided with two lugs 42 which engage sockets 43 formed in rings suitably spaced. The inner extremity, however, of one blade 41 has a relatively large lug 42 which engages a recess of corresponding size formed in the middle ring of the series, 90 which is approximately double the thickness of the other rings. It should be remembered, however, that no two blades are connected with the same anchoring rings, thus leaving the inner extremities of the blades 95 absolutely free to assume their varying positions independently of each other during the rotation of the eccentric element which determines the positions of the inner extremities of the blades. The outer extremities 100 46 of these blades are approximately cylindrical in shape and occupy recesses 47 of counterpart shape formed in the body of the structure, whereby the said extremities 46 are free to move within their sockets 105 or recesses in virtually the same manner as the lugs 42 which engage recesses or sockets in the rings 44, as heretofore explained. The outer extremities 46 of the blades are 110 approximately cylindrical in shape and 115

preferably extend the entire length of the body of the structure between the two heads 6.

The eccentric element 40 is so mounted 5 that the side farthest from the center of the driven shaft, approaches the inner surface of the body of the structure, sufficiently near to reduce the space or volume between the two adjacent blades to almost nothing, and 10 it is during the time that these blades are approaching such a position that the air is compressed and forced out of the compartment between the blades by opening one of the valves 28, as there is but one check 15 valve controlled exit port which may be designated 48 for each compartment 49 of the chamber 26. As soon as the two uppermost blades 41 (see Fig. 5) have reached said position, the space or volume between them is reduced to its smallest limit, and consequently as the eccentric element continues its rotary action the space or volume between these blades begins to enlarge, and the resulting vacuum tendency opens the 25 corresponding inlet valve piece 14, which is in communication with the annular chamber 9, whereby the air is drawn into the said compartment, until the compartment has attained its maximum volume by virtue of 30 the separation of the blades 41 from the position shown at the top of Fig. 5 to the position shown at the bottom of the same figure, the pair of lower blades under consideration being the one in the extreme low 35 position and the one immediately at the left. Between these two positions the volume or space between the blades is continually expanding and changes from the minimum to the maximum volume. Then, as 40 the rotation of the eccentric continues, the blades which are in position to give the compartment between them its greatest volume, begin to contract or diminish said volume and this contracting or diminishing 45 operation continues until the pair of blades in question reaches the collapsed position. (See Fig. 5). From this it will be understood, assuming that there are eight compartments 49 of the chamber 26, that four 50 of these compartments will be expanding and drawing in air, while the other four compartments are contracting and compressing the air, the compressed air from each compartment beginning to escape when 55 the pressure in the compression chamber sufficiently exceeds the pressure within the annular chamber 10 to overbalance the latter.

It will be understood that the inlet valve pieces 14 will remain open until the expanding compartment has reached its maximum expansion, but will close practically as soon as compression commences, since there is practically only atmospheric pressure on 60 their outer surface, plus the tension of the

springs 19, which are comparatively weak and, therefore, negligible.

It will be understood that as soon as the minimum volume between any two blades has been reached, whereby the air has been 70 expelled from the compartment between them, and the said space of compartment begins to expand, the exhaust check valves 28 will close, due to the exterior pressure in the chamber 10 and the vacuum tendency 75 in the compartment between the blades due to the changing position of the blades resulting in the expansion of the compartment. The springs 33 also have a slight 80 influence in returning the valves 28 to their seated position.

It must be understood that the annular chamber 9 and the annular exhaust or receiving chamber 10 each has a check valve controlled inlet port and a check valve controlled outlet port for each compartment or space between any two blades, and that this is constantly true, regardless of the space or volume between the blades; that is to say, whether this volume is reduced to the minimum or increased to the maximum degree, or whether the said space or volume is of any degree intermediate the minimum and maximum. These inlet and exit valves are arranged in pairs, being alined in a direction parallel with the axis of the driven shaft. It is also true that through the instrumentality of the inlet valves, the annular chamber 9 is successively placed in communication with the compartments 49, 90 while the same compartments are successively placed in communication with the annular exhaust or receiving chamber 10 through the instrumentality of the exit or 95 exhaust valves, during which last mentioned time the annular chamber 9 is cut off from the compartments 49, which are in communication with the receiving chamber 10. The inlet chamber 9 has an inlet pipe 100 50 threaded into the body of the structure, as shown at 51, while the exhaust or receiving chamber 10 has a pipe 52 in communication therewith, the same being threaded into the body of the structure, as shown at 53. This pipe 52 may lead to any desired 105 position, which may be convenient for the distribution of the compressed air. 110

The body of the machine is inclosed by and mounted upon a casing 54, which incloses the reinforced outer portion of the body of the structure, in which the annular chambers 9 and 10 are formed. This casing is composed of two members 55 having inwardly projecting flanges 56 which engage 120 circular ledges or shoulders 57 formed just inside the heads 6 of the body of the machine. The outer portion 8 of the body of the structure is provided with projections 58, which the flanges 56 of the casing members engage. These members are secured to 125 130

the body of the machine by means of bolts 59 which pass through the flanges 56, and enter threaded openings formed in lugs 58. This casing forms a water jacket, whose 5 chamber 61 surrounds the body of the compressor and performs the cooling function. The water jacket chamber has an inlet 62 and an outlet 63. (See Fig. 5.)

The two members 55 of the casing are 10 connected at the bottom by bolts 64 which pass through the abutting lugs or flanges 65. These casing members are also connected at the top by passing relatively long bolts 66 through openings formed in reinforcing lugs 67 formed integral with the casing at the top and having shoulders 68 against which the heads of the bolts and the nuts respectively abut. The lower portions of these outer casing members merge 15 into supporting legs 69 arranged on opposite sides of the machine.

From the foregoing description the use and operation of my improved air-compressor will be readily understood. Assuming 20 that the parts of the machine are in the relative positions shown in Fig. 5, if the shaft 38 is rotated by applying any suitable power thereto, the eccentric 46 will rotate therewith. This operation of the eccentric will immediately begin to expand or increase the volume between the two uppermost blades 41, and this expansion will continue until the compartment 49 reaches the maximum expansion as indicated at the 25 left of the lowermost blade, from which position this compartment will decrease in volume, whereby the air is compressed to the desired degree and finally forced out of the compartment through the corresponding valve controlled exhaust port 48. It will be understood that during the 30 operation of expanding the compartment 49, the air has been continually drawn into the said compartment by virtue of the vacuum 35 tendency due to such expansion.

While I have just referred to the operation of expanding and contracting a single compartment between two of the blades 41, it will be understood that the same operation 40 takes place with reference to each of the other compartments into which the chamber 26 is formed by the blades 41. The air enters the compartments 49 through the check valve controlled inlet ports from the 45 annular chamber 9, which receives its supply from the atmosphere through an inlet pipe 50. In order to form fluid tight joints between the compartments 49 at the inner extremities of the blades 41, the centers of 50 the cylindrical lugs 42 are made co-incident with the peripheral surfaces of the rings which the said lugs engage and the inner extremities of the bodies of the blades terminate at the axial centers of the said lugs, 55 whereby these extremities of the blades are

always in contact with the rings regardless of the position of the blades during the collapsing and expanding operation.

Having thus described my invention, what I claim is:

1. An air compressor or similar apparatus comprising a chamber, an eccentric mounted to rotate therein on an axis coincident with that of the chamber, rings surrounding the eccentric and loose thereon, the chamber having a compartment provided with collapsible walls whose extremities are movably mounted in the wall of the chamber and the eccentric rings, respectively, to alternately expand and contract the compartment as the eccentric is rotated, certain of the blades being each connected with a plurality of rings. 70

2. Apparatus of the class described comprising a chamber, a cylindrical element eccentrically mounted to rotate therein on an axis coincident with that of the chamber, rings surrounding said element and loose thereon, blades having their extremities movably mounted in the wall of the chamber and the said rings, respectively, to form a collapsible compartment adapted to be alternately expanded and contracted as the said element is rotated, certain of the blades being each connected with a plurality of rings. 85

3. Apparatus of the class described comprising a chamber, an element eccentrically mounted to rotate therein, rings surrounding said element and loose thereon, blades 100 having their extremities movably mounted in the wall of the chamber and the said rings, respectively, to form a collapsible compartment adapted to be alternately expanded and contracted as the said element is 105 rotated, the wall of the chamber being provided with check valve controlled inlet and exhaust ports communicating with the said compartment. 105

4. Apparatus of the class described comprising a chamber, a cylindrical element eccentrically mounted to rotate therein on an axis coincident with that of the chamber, rings surrounding said element and loose thereon, blades having their extremities 115 movably mounted in the wall of the chamber and the said ring, respectively, to form a collapsible compartment adapted to be alternately expanded and contracted as the said element is rotated, the wall of the 120 chamber being provided with check valve controlled inlet and exhaust ports communicating with the said compartment and leading respectively to the atmosphere and a receiver. 125

5. Apparatus of the class described comprising a chamber, a cylindrical element eccentrically mounted to rotate therein, its axis of rotation being coincident with that of the chamber, rings surrounding said ele- 130

ment and loose thereon, blades having their extremities movably mounted in the wall of the chamber and the rings respectively to form a collapsible compartment adapted 5 to be alternately expanded and contracted as the said element is rotated, the wall of the chamber having check valve controlled inlet and exhaust ports communicating with the compartment and a compressed air receiver 10 formed in the wall of the chamber and in communication with the exhaust port.

6. Apparatus of the class described comprising a chamber, a cylindrical element eccentrically mounted therein, to rotate on the axis of said chamber a series of rings surrounding said element, and loose thereon, blades having their outer extremities movably anchored in the wall of the chamber 15 and their inner extremities movably connected with the said rings, the blades being spaced to form collapsible compartments in said chamber, certain of the blades being each connected with a plurality of rings, the 20 respective blades being connected with different rings to permit independent automatic adjustment during the rotation of said element.

7. Apparatus of the class described comprising a chamber, a cylindrical element eccentrically mounted in said chamber, to rotate on the axis of the latter rings surrounding said element and loose thereon, blades having their outer extremities movably anchored in the wall of the chamber, and their inner extremities movably anchored in the rings, the several blades being connected 25 with different rings to permit independent automatic adjustment, certain of the blades being each connected with a plurality of rings, the extremities of the adjacent blades being spaced to divide the said chamber into collapsible compartments which are successively expanded and contracted as the eccentrically mounted element is rotated.

8. Apparatus of the class described comprising a chamber, a cylindrical element eccentrically mounted to rotate in said chamber, and having its axis of rotation coincident with the axis of the chamber, rings surrounding said element and loose thereon, blades having their outer extremities movably anchored in the wall of the chamber, 30 and their inner extremities movably anchored in the rings, the several blades being connected with different rings to permit independent automatic adjustment, the extremities of the adjacent blades being spaced to divide the said chamber into collapsible compartments which are successively expanded and contracted as the eccentrically mounted element is rotated, the several compartments having automatic valve controlled inlet and exhaust ports.

9. Apparatus of the class described comprising a chamber, a cylindrical element eccentrically mounted to rotate in said chamber, its axis of rotation being coincident with the axis of the chamber, rings surrounding said element and loose thereon, blades having 35 their outer extremities movably anchored in the wall of the chamber, and their inner extremities movably anchored in the rings, the several blades being connected with different rings to permit independent automatic adjustment, the extremities of the adjacent blades being spaced to divide the said chamber into collapsible compartments which are successively expanded and contracted as the eccentrically mounted element is rotated, each compartment having a distinct set of check valve controlled inlet and exhaust ports, the wall of the chamber being also equipped with an annular receptacle for atmospheric air to which the inlet ports lead.

10. Apparatus of the class described comprising a chamber, a cylindrical element eccentrically mounted to rotate in said chamber, its axis of rotation being coincident with the axis of the chamber, rings surrounding said element and loose thereon, blades having 40 their outer extremities movably anchored in the wall of the chamber, and their inner extremities movably anchored in the rings, the several blades being connected with different rings to permit independent automatic adjustment, the extremities of the adjacent blades being spaced to divide the said chamber into collapsible compartments which are successively expanded and contracted as the eccentrically mounted element is rotated, each compartment having a distinct set of check valve controlled inlet and exhaust ports, the wall of the chamber being also equipped with an annular receptacle for atmospheric air to which the inlet ports lead.

11. Apparatus of the class described comprising a chamber, a cylindrical element eccentrically mounted in said chamber, to rotate on an axis coincident with the axis of the chamber, rings surrounding said element and loose thereon, blades having their outer extremities movably anchored in the wall of the chamber, and their inner extremities movably anchored in the rings, the several blades being connected with different rings to permit independent automatic adjustment, the extremities of the adjacent blades being spaced to divide the said chamber into collapsible compartments which are successively expanded and contracted as the eccentrically mounted element is rotated, each compartment having a distinct set of check valve controlled inlet and exhaust ports, the wall of the chamber being also equipped with an annular receptacle for atmospheric air to which the inlet ports lead.

12. Apparatus of the class described comprising a chamber, a shaft passing axially therethrough and journaled therein, a cylindrical element eccentrically mounted on said shaft to rotate therewith, rings surrounding said element and loose thereon, curved blades

130

having their opposite extremities respectively movably anchored in the wall of the chamber and the said rings to permit independent automatic adjustment of their ring extremities, certain of the blades being each connected with a plurality of rings, the extremities of each pair of adjacent blades being spaced to divide the said chamber into collapsible compartments which are alternately expanded and contracted as the shaft and its eccentrically mounted element are rotated.

13. Apparatus of the class described comprising a chamber, a shaft passing axially therethrough and journaled therein, a cylindrical element eccentrically mounted on said shaft to rotate therewith, rings surrounding said element and loose thereon, curved blades having their opposite extremities respectively movably anchored in the wall of the chamber and the said rings to permit independent automatic adjustment of their ring extremities, the extremities of each pair of adjacent blades being spaced to divide the said chamber into collapsible compartments which are alternately expanded and contracted as the shaft and its eccentrically mounted element are rotated, each compartment having check valve controlled inlet and exhaust ports.

14. Apparatus of the class described comprising a chamber, a shaft passing axially therethrough and journaled therein, a cylindrical element eccentrically mounted on said shaft to rotate therewith, rings surrounding said element and loose thereon, curved blades having their opposite extremities respectively movably anchored in the wall of the chamber and the said rings to permit independent automatic adjustment of their ring extremities, the extremities of each pair of adjacent blades being spaced to divide the said chamber into collapsible compartments which are alternately expanded and contracted as the shaft and its eccentrically mounted element are rotated, each compartment having check valve controlled inlet and exhaust ports, and annular chambers formed in the wall of the compression chamber to which the inlet and exhaust ports respectively lead, and an outer casing applied to the body of the compressor and provided with a water chamber surrounding the annular chambers formed in the wall of the compression chamber.

15. Apparatus of the class described comprising a chamber, a shaft passing axially therethrough and journaled therein, a cylindrical element eccentrically mounted on said shaft to rotate therewith, rings surrounding said element and loose thereon, curved blades having their opposite extremities respectively movably anchored in the wall of the chamber and the said rings to permit independent automatic adjustment of their ring extremities, the extremities of each pair of adjacent blades being spaced to divide the said chamber into collapsible compartments which are alternately expanded and contracted as the shaft and its eccentrically mounted element are rotated, each compartment having check valve controlled inlet and exhaust ports, and annular chambers formed in the wall of the compression chamber to which the inlet and exhaust ports respectively lead.

16. Apparatus of the class described comprising a chamber, a shaft passing axially therethrough and journaled therein, a cylindrical element eccentrically mounted on said shaft to rotate therewith, rings surrounding said element and loose thereon, curved blades having their opposite extremities respectively movably anchored in the shaft and its eccentrically mounted element are rotated, each compartment having check valve controlled inlet and exhaust ports, and annular chambers formed in the wall of the compression chamber to which the inlet and exhaust ports respectively lead, and an outer casing applied to the body of the compressor and provided with a water chamber surrounding the annular chambers formed in the wall of the compression chamber, the water chamber having inlet and exhaust ports.

17. Apparatus of the class described comprising a chamber, a shaft passing axially therethrough and journaled therein, a cylindrical element eccentrically mounted on said shaft to rotate therewith, rings surrounding said element and loose thereon, curved blades having their opposite extremities respectively movably anchored in the wall of the chamber and the said rings to permit independent automatic adjustment of their ring extremities, the extremities of each pair of adjacent blades being spaced to divide the said chamber into collapsible compartments which are alternately expanded and contracted as the shaft and its eccentrically mounted element are rotated, each compartment having check valve controlled inlet and exhaust ports, and annular chambers formed in the wall of the compression chamber to which the inlet and exhaust ports respectively lead, and an outer casing applied to the body of the compressor and provided with a water chamber surrounding the annular chambers formed in the wall of the compression chamber.

18. Apparatus of the class described comprising a chamber, a shaft passing axially therethrough and journaled therein, a cylindrical element eccentrically mounted on said shaft to rotate therewith, rings surrounding said element and loose thereon, curved blades having their opposite extremities respectively movably anchored in the wall of the chamber and the said rings to permit independent automatic adjustment of their ring extremities, the extremities of each pair of adjacent blades being spaced to divide the said chamber into collapsible compartments which are alternately expanded and contracted as the shaft and its eccentrically mounted element are rotated, each compartment having check valve controlled inlet and exhaust ports, and annular chambers formed in the wall of the compression chamber to which the inlet and exhaust ports respectively lead, and an outer casing applied to the body of the compressor and provided with a water chamber surrounding the annular chambers formed in the wall of the compression chamber, the water chamber having inlet and exhaust ports.

19. Apparatus of the class described comprising an interior and an exterior element mounted in eccentric relation, one of said elements being rotatable, rings loosely mounted on the interior element, and blades, whose opposite extremities are movably anchored on the exterior element and in the rings of the interior element, respectively, certain of the blades being each connected with a plurality of rings, said blades being spaced to form a collapsible compartment adapted to be expanded and contracted during the movement of the rotary element, the two elements being arranged to form an interposed chamber.

20. Apparatus of the class described comprising interior and exterior elements mounted in eccentric relation to form an interposed chamber, one of said elements being rotatable, a series of rings loosely mounted on the interior element, blades whose opposite extremities are movably anchored in the exterior element and in the rings of the interior element, respectively, certain of the blades being each connected with a plurality of rings, the extremities of the blades being spaced to form the chamber into a number of collapsible compartments.

ments adapted to be successively expanded and contracted during the movement of the rotary element.

19. Apparatus of the class described, comprising an interior and an exterior element mounted in eccentric relation to form an interposed chamber, one of said elements being rotatable, the interior element having engaging rings free to move rotatably thereon, and blades whose opposite extremities are respectively movably mounted in the rings of one element, and in the wall of the other element, certain of the blades being each connected with a plurality of rings.

15 20. Apparatus of the class described, comprising an interior and an exterior element mounted in eccentric relation to form an interposed chamber, one element being rotatable, the interior element having loose rings, and blades whose opposite extremities are respectively movably anchored in the rings of one element and in the wall of the other element, the extremities of the blades being spaced to form the chamber into collapsible compartments which are expanded and contracted during the movement of the rotary element, certain of the blades being each connected with a plurality of rings.

21. Apparatus of the class described, comprising an interior element and an exterior element, the two elements being mounted in eccentric relation, one element being rotatable, the interior element having rings loose thereon, and blades whose opposite extremities are respectively movably connected with the rings of one element and with the wall of the other element, the extremities of the blades being spaced to form the chamber into collapsible compartments which are expanded and contracted during the movement of the rotary element, the machine being provided with a distinct set of check valve controlled inlet and exhaust ports for each collapsible compartment.

45 22. Apparatus of the class described, comprising interior and exterior elements arranged in eccentric relation to form an interposed chamber, one element being mounted to rotate while the other element is stationary, the interior element having rings circumferentially engaging the same and free to turn thereon, blades whose opposite extremities are respectively movably anchored in the rings of the interior element and the wall of the other element, certain of the blades being each connected with a plurality of rings, the extremities of the blades being spaced to form the said chamber into collapsible compartments which are expanded and contracted during the movement of the rotary element.

23. Apparatus of the class described, comprising two elements arranged one within the other in eccentric relation, one being stationary and the other rotatable, the rotatable

element being mounted in such relation to the stationary element that its axial center is beyond the axial center of the stationary element, the interior element having rings loose thereon, and blades whose opposite extremities are respectively movably anchored in the rings of the interior element, certain of the blades being each connected with a plurality of rings, and the wall of the exterior element, the extremities of the blades being spaced to form the said chamber into collapsible compartments which are expanded and contracted during the movement of the rotary element, the structure being provided with inlet and exhaust ports for the collapsible compartments.

24. Apparatus of the class described comprising a chamber, an element eccentrically mounted to rotate therein, a sleeve surrounding said element, rings surrounding said sleeve and loose thereon and blades having their extremities movably mounted in the walls of the chamber and the said rings, respectively, to form a collapsible compartment adapted to be alternately expanded and contracted as the said element is rotated, certain of the blades being each connected with a plurality of rings.

25. Apparatus of the class described comprising a chamber, an element eccentrically mounted therein, a sleeve surrounding said element, a series of rings surrounding said sleeve, blades having their outer extremities movably anchored in the wall of the chamber and their inner extremities movably connected with said rings, certain of the blades being each connected with a plurality of rings, the blades being spaced to form collapsible compartments in said chamber, the respective blades being connected with different rings to permit independent automatic adjustment during the rotation of said element.

26. Apparatus of the class described comprising a chamber, an element eccentrically mounted to rotate therein, rings surrounding said element and loose thereon, blades having their extremities movably mounted in the walls of the chamber and the said rings, respectively, to form a collapsible compartment adapted to be alternately expanded and contracted as the said element is rotated, the extremities of the blades which engage the rings, being provided with cylindrical lugs whose centers are co-incident with the peripheral surface of the rings, the inner extremities of the bodies of the blades extending to said centers of the lugs, whereby fluid tight joints are formed between the compartments, substantially as described.

27. An air compressor or similar apparatus comprising a cylindrical chamber, a cylindrical element mounted to revolve around the axis of the chamber as a center, said axis passing through said element be-

- yond its true center, rings surrounding said element and loose thereon, the chamber having a compartment provided with collapsible walls whose outer extremities are movably mounted and largely concealed within the wall of the chamber, the inner extremities of certain of the collapsible walls being each pivotally connected with a plurality of rings. 5
28. Apparatus of the class described comprising a cylindrical chamber, a cylindrical element mounted to revolve around the axis of the chamber which passes through said element beyond its center, rings surrounding the said element and loose thereon, and blades having their outer extremities movably mounted and largely embedded in the wall of the chamber, the inner extremities of certain of the blades being each pivotally connected with a plurality of rings, to form a collapsible compartment adapted to be alternately expanded and contracted as the said element is revolved. 10
29. Apparatus of the class described comprising a cylindrical chamber, a cylindrical element mounted to revolve therein around the axis of the chamber, which passes longitudinally through the said element between its center and its periphery, rings surrounding the said element and loose thereon, and blades having their outer extremities movably mounted and embedded in the wall of the chamber, the inner extremities of certain of the blades being each pivotally connected with a plurality of rings, to form a collapsible compartment adapted to be alternately expanded and contracted as the said element is revolved. 15
30. Apparatus of the class described comprising a cylindrical chamber, a cylindrical element mounted to revolve therein around the longitudinal axis of the chamber, which passes longitudinally through said element between its center and its periphery and parallel with the latter, rings surrounding said element and loose thereon, blades having their outer extremities movably mounted and embedded in the wall of the chamber and the inner extremities of certain of the blades being each pivotally connected with a plurality of rings, to form a collapsible compartment adapted to be alternately expanded and contracted as the said element is rotated, and means for controlling the fluid inlet and exhaust to and from the chamber. 20
31. Apparatus of the class described comprising a cylindrical chamber, an interior and exterior element mounted in eccentric relation, one of said elements being rotatable, rings loosely mounted on the interior element, through which the axis of the chamber passes longitudinally between its center and its periphery and parallel with the latter, and blades whose outer extremi- 25
- ties are movably anchored and embedded in the exterior element, the inner extremities of certain of the blades being each pivotally connected with a plurality of rings, said blades being spaced to form a collapsible compartment adapted to be expanded and contracted during the movement of the rotary element, the two elements being arranged to form an interposed compartment within said chamber. 30
32. Apparatus of the class described comprising a cylindrical chamber, interior and exterior elements mounted in eccentric relation to form an interposed compartment, one of said elements being rotatable, a series of rings loosely mounted on the interior element, blades whose outer extremities are movably anchored and embedded in the exterior element and whose inner extremities are hingedly connected with the rings, certain of the blades being each pivotally connected with a plurality of rings, the extremities of the blades being spaced to form the said interposed compartment into a number of collapsible subdivisions adapted to be successively expanded and contracted during the movement of the rotary element, the aggregate length of all the blades being equal approximately to the circumference of the chamber. 35
33. Apparatus of the class described comprising a cylindrical chamber, an interior and an exterior element mounted in eccentric relation to form an interposed compartment, one of said elements being rotatable, the interior element having engaging rings free to move rotatably thereon, and blades whose opposite extremities are respectively hingedly connected with the rings of one element and movably embedded in the wall of the other element, certain of the blades being each connected with a plurality of rings, the aggregate length of the said blades being substantially equal to the circumference of the chamber. 40
34. Apparatus of the class described comprising a cylindrical chamber, an interior and an exterior element mounted in eccentric relation to form an interposed compartment, one element being rotatable, the interior element having loose rings, and blades whose opposite extremities are respectively hingedly connected with the rings of one element and movably embedded in the wall of the other element, certain of the blades being each pivotally connected with a plurality of rings, the extremities of the blades being spaced to form the interposed compartment into a number of collapsible subdivisions which are expanded and contracted during the movement of the rotary element, the aggregate length of all the blades being substantially equal to the circumference of the said chamber. 45
35. Apparatus of the class described com- 50

- prising a cylindrical chamber, an interior element and an exterior element, the two elements being mounted in eccentric relation, one element being rotatable, the interior element having rings loose thereon, and blades whose opposite extremities are respectively hingedly connected with the rings of one element and movably embedded in the wall of the other element, certain of the blades being each connected with a plurality of rings, the extremities of the blades being spaced to form the said compartment into a number of collapsible subdivisions which are expanded and contracted during the movement of the rotary element, the aggregate length of all the blades being substantially equal to the circumference of the said chamber, and means for regulating the inlet and exhaust to and from the several collapsible subdivisions of the interposed chamber.
36. Apparatus of the class described comprising a cylindrical chamber, interior and exterior elements arranged in eccentric relation to form an interposed compartment, one element being mounted to rotate while the other element is stationary, the interior element having rings circumferentially engaging the same and free to turn thereon, blades whose opposite extremities are respectively movably anchored and embedded in the interior element and hingedly connected with the rings of the interior element, certain of the blades being each connected with a plurality of rings, the extremities of the blades being spaced to form the said interposed compartment into a number of collapsible subdivisions which are expanded and contracted during the movement of the rotary element, the said blades being curved to conform approximately to the circumference of the chamber, their aggregate length being substantially equal to such circumference.
37. Apparatus of the class described comprising a cylindrical chamber, two elements arranged one within the other, one being stationary and the other rotatable, the rotatable element being mounted in such relation to the stationary element that its axial center is beyond the axial center of the stationary element, the interior element having rings loose thereon, and blades whose extremities are respectively movably anchored and embedded in the exterior element and hingedly connected with the rings of the interior element, certain of the blades being each connected with a plurality of rings, the extremities of the blades being spaced to form the space between the two elements into collapsible compartments which are expanded and contracted during the movement of the rotary element and means for controlling the inlet and exhaust to and from the said compartments.
38. Apparatus of the class described, comprising a chamber, an eccentric mounted to rotate therein on the axis of the chamber, rings surrounding the eccentric and loose thereon, the chamber having a compartment provided with collapsible walls whose extremities are movably mounted in the wall of the chamber and the eccentric rings respectively to alternately expand and contract the compartment as the eccentric is rotated, and means independent of the rings for forming tight joints between the rings and the collapsible walls.
39. The combination of a chamber, a cylindrical element eccentrically mounted to rotate therein on an axis coincident with that of the chamber, rings surrounding said element and loose thereon, blades having their extremities movably mounted in the wall of the chamber and the said rings respectively to form a collapsible compartment adapted to be alternately expanded and contracted as the said element is rotated, and means independent of the rings with which any blade is connected for forming a tight joint between the blade and the other rings.
40. The combination of an interior and an exterior element mounted in eccentric relation, one of said elements being rotatable, rings loosely mounted on the interior element, blades whose opposite extremities are movably anchored in the exterior element and in the rings of the interior element, said blades being spaced to form a collapsible compartment adapted to be expanded and contracted during the movement of the rotary element, the two elements being arranged to form an interposed chamber, and means independent of the rings for forming tight joints between the rings and the blades.
41. Apparatus of the class described, comprising interior and exterior elements mounted in eccentric relation to form an interposed chamber, one of said elements being rotatable, a series of rings loosely mounted on the interior element, blades whose opposite extremities are movably anchored in the exterior element and in the rings of the interior element respectively, the extremities of the blades being spaced to form the chamber into a number of collapsible compartments adapted to be successively expanded and contracted during the movement of the rotary element, and means independent of the rings with which any blade is connected for forming a tight joint between the blade and the other rings.
42. Apparatus of the class described, comprising an interior and an exterior element mounted in eccentric relation to form an interposed chamber, one of said elements being rotatable, the interior element having engaging rings free to move relatively

thereon, blades whose opposite extremities are respectively movably mounted in the rings of one element and in the wall of the other element, and means independent of the rings for forming tight joints between the rings and the blades.

43. Apparatus of the class described, comprising an interior and an exterior element mounted in eccentric relation to form an interposed chamber, one element being rotatable, the interior element having loose rings, blades whose opposite extremities are respectively movably anchored in the rings of one element and in the wall of the other element, the extremities of the blades being spaced to form the chamber into collapsible compartments which are expanded and contracted during the movement of the rotary element, and means independent of the rings for forming tight joints between the rings and the blades.
44. Apparatus of the class described, comprising an interior element and an exterior

element, the two elements being mounted in eccentric relation to form an interposed chamber, one element being rotatable, the interior element having rings loose thereon, blades whose opposite extremities are respectively movably connected with the rings of one element and with the wall of the other element, the extremities of the blades being spaced to form the chamber into collapsible compartments which are expanded and contracted during the movement of the rotary element, the machine being provided with controlled inlet and exhaust ports for each collapsible compartment, and means independent of the blades for forming tight joints between the blades and the rings.

In testimony whereof I affix my signature in presence of two witnesses.

HENRY O. JACKSON.
